[57] ABSTRACT

A tone-color forming circuit in an electronic musical instrument comprises fundamental tone and second harmonic tone producing circuits operable in mutual in-phase relationship, a first switching circuit of a longer decaying time connected with the outputs of the fundamental and second harmonic producing circuits, a second switching circuit of a shorter decaying time connected with the output of the fundamental tone producing circuit and with the phase-reversed output of the second harmonic producing circuit, a first filter and a second filter of different characteristics coupled respectively with the outputs of the first and second switching circuits, and a mixing circuit, whereby a musical tone signal of double-fold decay can be obtained from the mixing circuit.

TONE-COLOR FORMING CIRCUIT IN ELECTRONIC MUSICAL INSTRUMENT

BACKGROUND OF THE INVENTION

This invention relates to tone-color forming circuits in electronic musical instruments, and more particularly to a new and advanced circuit capable of producing instrument signals simulating the sound of a bass guitar or the like having a double-fold attenuation characteristic accompanied by variation in tone-color.

As is well known, a musical instrument such as a bass guitar produces a musical tone characterized by double-fold decay accompanied by varying tone-color. Heretofore, when attempts were made to simulate the bass guitar or the like in an electronic musical instrument, difficulties have been encountered in the creation of the double-fold decaying features, and as far as I am aware, none of such attempts have yet succeeded in creating a music tone compatible with that of the bass guitar or the like.

SUMMARY OF THE INVENTION

Therefore, a primary object of the present invention is to provide tone-color forming circuit in an electronic musical instrument which can simulate the sound of a bass guitar or the like.

Another object of the invention is to provide a tone-color forming circuit in an electronic musical instrument which can create a tone-color simulating the bass guitar or the like, wherein is included a second harmonic component in addition to the fundamental tone, and the second harmonic component reappears after it has once disappeared during the attenuation of the resultant music tone.

These and other objects of the present invention can be achieved by a tone-color forming circuit in an electronic musical instrument, which circuit comprises a fundamental tone producing circuit, a second harmonic producing circuit producing two signals of the same frequency but of a reversed phase relation, a first switching circuit of a longer decaying time characteristic coupled with the outputs of these fundamental and second harmonic producing circuits, a second switching circuit of a shorter decaying time characteristic coupled with the outputs of these two circuits but in the reversed phase (polarity) for the output of the second harmonic producing circuit, first and second filters of different tone-color characteristics coupled respectively to the outputs of said first and second switching circuits, and a mixing circuit for mixing the outputs of these filters, whereby a music tone signal of a double-fold decaying envelope can be obtained from the mixing circuit.

The nature, principle, and the utility of the present invention will be more clearly understood from the hereinafter described detailed description of the invention with respect to a preferred embodiment thereof when read in conjunction with the accompanying drawings.

BRIEF DESCRIPTION OF THE DRAWINGS

In the drawings:

FIG. 1 is a block diagram of a tone-color forming circuit according to the present invention;

FIGS. 2(a) and 2(b) are characteristic curves representing the characteristics of switching circuits included in the circuit shown in FIG. 1;

FIGS. 3(a) and 3(b) are characteristic curves representing the characteristics of filters included in the circuit shown in FIG. 1; and

FIGS. 4(a) and 4(b) are diagrams showing the envelope curves of 8' and 4' tone signals included in the output musical tone signal of this circuit.

DETAILED DESCRIPTION OF THE INVENTION

Referring to FIG. 1 showing a tone-color forming circuit constituting an embodiment of the present invention, a tone signal is applied to an input terminal T_1 of the tone-color forming circuit and hence to a flip-flop 1 of 4-foot register tone. The output of the 4-foot register flip-flop 1 is then applied to an 8-foot register flip-flop 2 to be frequency-divided therein into one-half. The 8-foot register tone corresponds to a fundamental tone for the tone-color forming circuit, and the 4-foot register tone corresponds to a second harmonic tone for the same circuit.

20 A signal applied to an input terminal T_1 does not include only one special frequency. The frequencies so applied are decided by what particular note switching circuits share in. Assuming for instance that the switching circuits share in C₄-note (fundamental frequency = 25 261.6 Hz), an output frequency from the flip-flop 2 is 261.6 Hz and an output frequency from the flip-flop 1 is 523.3 Hz. Accordingly, an input frequency to the flip-flop 1 becomes 1046.5 Hz. In general, four-foot register means a resistor wherein the produced tones 30 have frequencies which are respectively one octave higher than nominal frequencies. Since the flip-flop operates to divide an input frequency by one-half, it is necessary to previously apply to the input terminal a tone signal having a frequency one octave higher than that of 4-foot register tone in order to obtain the 4-foot register tone from the flip-flop 1.

From terminals T_2 and T_3 of the 4-foot register flip-flop 1, two 4-foot register tone signals of mutually opposite phase relationship are produced and are supplied to switching circuits 3 and 4, respectively. The output signal from the flip-flop 2 for 8-foot register tone is delivered from a terminal T_4 thereof supplied to both of the switching circuits 3 and 4.

45 The decaying characteristic of the switching circuit 3 is selected to be one which gradually decays within about 1,000 milliseconds as shown in FIG. 2(a). The output signal from the switching circuit 3 is passed through a low-pass filter 5 of a characteristic such that a frequency component lower than about 130 Hz is emphasized as indicated in FIG. 3(a). The output signal from the filter 5 is thereafter supplied to a mixing circuit 7.

50 On the other hand, the decaying characteristic of the switching circuit 4 is of a kind which sharply decays within 100 milliseconds as shown in FIG. 2(b). The output signal from the switching circuit 4 is thereafter passed through a resonance type filter 6 of a characteristic as shown in FIG. 3(b) such that a frequency portion near about 500 Hz is emphasized. The output from the filter 6 is also supplied to the mixing circuit 7. Within the mixing circuit 7, the output signals from the filters 5 and 6 are mixed, and the output signal of this tone-color forming circuit is obtained from an output terminal T_5 of the mixing circuit 7.

60 It is to be noted that the signal level of the output of the switching circuit 4 is selected to be higher than that of the output of the switching circuit 3. In the tone-

color forming circuit thus organized and set, when the 8-foot tone signal only is taken into consideration, the two output signals of the same flip-flop 2 for 8-foot register tone, which are of the same phase, are switched respectively in the switching circuits 3 and 4, which have predetermined decaying characteristics as described above, and are then passed through the low-pass filter 5 and the resonance type filter 6 to the mixing circuit 7.

As to the switching circuits 3 and 4, it will be apparent to those skilled in the art that suitable structure may be chosen therefor in a manner that the signal level of the output of switching circuit 4 is higher than the signal level of the switching circuit 3. An example of suitable structure for the switching circuits may be derived from the illustration in U. S. Pat. No. 3,170,020.

Accordingly, the envelope of the resultant 8-foot tone signal obtained from the mixing circuit 7 has an envelope curve as shown in FIG. 4(a) rapidly decaying during the initial 100 milliseconds and slowly decaying 20 during the remaining 900 milliseconds.

When the 4-foot tone signal is now taken into consideration, two output signals of 4-foot tone, in an opposite phase relationship to each other, are respectively passed through the switching circuits 3 and 4 and the 25 low-pass filter 5 and the resonance type filter 6, respectively, to the mixing circuit 7.

Since the signal level of the output of the switching circuit 4 is selected to be higher than that of the output of the switching circuit 3, the output signal from the 30 mixing circuit 7 initially contains the 4-foot tone signal obtained from the terminal T_3 (of the opposite phase), whereby the 4-foot tone signal obtained from the terminal T_2 (of the primary phase) is cancelled. However, in the meantime, the 4-foot tone signal obtained from the 35 terminal T_3 decays more quickly than that obtained from the terminal T_2 depending on the characteristics of the switching circuits 3 and 4, and when the magnitudes of the 4-foot tone signals obtained from the terminals T_2 and T_3 become equal, the 4-foot tone signal component contained in the output of the mixing circuit 7 is nullified.

After this instant, because of the quick attenuation characteristic of the switching circuit 4, the 4-foot tone signal of the reversed phase obtained from the terminal T_3 fades, and the 4-foot tone signal in phase with the 8-foot tone signal obtained from the terminal T_2 is predominant in the output of the mixing circuit 7. After 45 100 milliseconds, no 4-foot tone signal exists in the output of the switching circuit 4. Thus, in the output of the mixing circuit 7, the initially appearing 4-foot tone signal disappears in the course of the decaying and then reappears as shown in FIG. 4(b).

Although in the above description, the 4-foot and 8-foot tone signal have been described separately, the ac- 55

tual output tone signal obtained from the mixing circuit 7 contains both of these component signals, whereby a variation effect in the tone color wherein the second harmonic component disappears once in the course of the decaying and reappears thereafter can be obtained in the output tone signal delivered from the mixing circuit 7. Such an effect of variation in the tone-color is further accentuated by the disposition of filters of low-pass and resonance characteristics at the subsequent 10 stages of the switching circuits 3 and 4, respectively.

By the above described organization of the tone-color forming circuit according to the present invention, a musical tone signal having double-fold attenuation characteristics accompanied by a tone-color variation during the attenuation can be obtained, and a musical instrument simulating the guitar and the like with naturalness of auditory sensation can be produced by employing the tone-color forming circuit according to the present invention.

I claim:

1. A tone-color forming circuit in an electronic musical instrument, comprising: a fundamental tone producing circuit; a second harmonic producing circuit producing two signals of the same frequency but of a reversed phase relationship; a first switching circuit having a predetermined decaying time connected with the output of said fundamental tone producing and the output of the second harmonic producing circuit without phase reversal, a second switching circuit having a decaying time shorter than said predetermined time and coupled with the output of said fundamental tone producing circuit and with the output in the reversed phase of the second harmonic producing circuit; a first filter and a second filter having outputs and being of different tone-color characteristics and coupled respectively with the outputs of the first and second switching circuits; and a mixing circuit for mixing the outputs of said filters, whereby a musical tone signal of an envelope having a double-fold decaying characteristic can be obtained from the mixing circuit.

2. A tone forming circuit as set forth in claim 1 wherein said first switching circuit of said predetermined decaying time has a decaying period of the order of 1,000 milliseconds, and said second switching circuit having a shorter decaying time has a decaying period of the order of 100 milliseconds.

3. A tone-color forming circuit as set forth in claim 1 wherein said first filter is made in the form of a low-pass filter, and said second filter is made in the form of a resonance type filter.

4. A tone-color forming circuit as set forth in claim 1 wherein an output level of said second switching circuit is selected to be higher than an output level of said first switching circuit.
